UNITED STATES PATENT OFFICE.

JULIUS BRENZINGER, OF FAIRFIELD, CONNECTICUT, ASSIGNOR TO MAX AMS CHEMICAL ENGINEERING CORPORATION, OF BRIDGEPORT, CONNECTICUT, A CORPORATION OF CONNECTICUT.

PUMP.

Application filed December 11, 1925. Serial No. 74,684.

- This invention relates to pumps of the type in which a rather exact quantity of fluid, such as the viscous material used for artificial silk, is delivered, and the main object and features of the invention is to provide means whereby the wear of the parts can be compensated for so as to retain the ability to deliver a measured quantity of fluid.
- 5 In the accompanying drawings the invention is disclosed in a concrete and preferred form in which:
- Fig. 1 is a general view in side elevation, showing a pump embodying the invention.
- 10 Fig. 2 is a vertical sectional view substantially on the plane of line 2—2 of Fig. 1.
- Fig. 3 is a vertical sectional view substantially on the plane of line 3—3 of Fig. 2.
- 15 Fig. 4 is a sectional view substantially on the plane of line 4—4 of Fig. 3.
- Fig. 5 is a perspective view of the filler members used in the device.
- In the art as heretofore practiced it has been customary to use two external spur gears or pinions meshing with each other as the pump elements, the material being conveyed in the spaces between the teeth and the casing. It has been found that, in such construction, the wearing down of the 20 teeth of the pinions produces a leakage between the teeth of the gears at the point where they mesh thus affecting adversely the measuring quality of the pump or its capacity to deliver a given amount with each revolution. This defect I overcome by using as the pump elements one internal and one external gear meshing with each other as I find that by this construction means can be readily provided to press the 25 gears into closer engagement to compensate for wear, and also it is more difficult for the material to work back between the teeth of the gears because more teeth are in mesh than in a construction involving the use of two external gears.
- 30

1 indicates a casing of any suitable construction but here conveniently composed of two members 2 and 3 bolted together as at 4 and having interposed between them a 35 plate 5 having a circular cut-away portion 6 that constitutes the pump chamber. 7 and 8 indicate respectively an inlet and an outlet to and from said pump chamber. Seated within the cut-away portion is an 40 annulus 9 having internal gear teeth and,

in the present instance, this annulus is simply a loose ring guided by the walls of the pump chamber. 10 is an external gear or pinion also contained within the pump chamber and meshing with the internal gear. Gear 10 is mounted on a shaft 11, driven from any suitable source, in such a way that a slight diametral motion is possible, this being indicated by the double line at 12. 13 and 14 are segmental shaped and taper filler members secured to member 2 by means of set screws 15 and occupy the space between the unmched parts of the gears.

It will now be understood that rotation 45 imparted to shaft 11 will cause gear 10 to impart a traveling motion to the annulus and that material entering from inlet 7 will be carried around on both sides of the filler members or guides 13 and 14 in the spaces 50 of the unmched parts of the teeth of both gears and will thence be delivered to outlet 8. Should now the gear teeth become worn it will be understood that the filler members or guides can be adjusted by reason of slots 55 16 to bring the gears more closely together to thereby prevent flow of fluid between the meshed parts of the teeth of the gears.

I claim:

1. A pump including: a casing having an 60 inlet and an outlet, and pumping elements embracing: an internal gear rotatable in said casing, and an external pinion, mounted to have a slight diametral motion, 65 also rotatable within said casing and meshing with the internal gear; and filler means to take up the wear of the gears by pressing them into closer engagement with each other.

2. A pump including: a casing having an 70 inlet and an outlet, and pumping elements embracing: an internal gear rotatable in said casing, and an external pinion, mounted to have a slight diametral motion, 75 also rotatable within said casing and meshing with the internal gear, and adjustable segmental shaped filler members within the casing and between the unmched parts of the gears to take up the wear of the gears 80 by pressing them into closer engagement 85 with each other.

3. A pump including: a casing having a circular-shaped pump chamber provided with an outlet and an inlet, segmental guides within the pump chamber, an annu- 90

lus having internal teeth loosely mounted within the pump chamber and surrounding the guides, an external gear mounted to have a slight diametral play, within the 5 chamber between the guides and the annulus and in mesh with the internal teeth of the latter, and means for adjusting the guides to bring the gear into closer engagement with the annulus.

10 4. A pump including: a casing having a circular-shaped pump chamber provided with an outlet and an inlet, segmental taper guides within the pump chamber, an an-

nulus having internal teeth loosely mounted within the pump chamber and surrounding 15 the guides, an external gear mounted to have a slight diametral play, within the chamber between the guides and the annulus and in mesh with the internal teeth of the latter, and means for adjusting the guides to bring the gear into closer engagement with the annulus.

Signed at Bridgeport in the county of Fairfield and State of Connecticut this 9th day of December, 1925.

JULIUS BRENZINGER.
